(57) **CLAIM**

The ornamental design for a pool skimmer net, as shown and described.

DESCRIPTION

FIG. 1 is a perspective view of the pool skimmer net showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 in FIG. 1;

FIG. 10 is a partial enlarged view of portion 10 in FIG. 2;

FIG. 11 is a partial enlarged view of portion 11 in FIG. 2; and,

FIG. 12 is a partial enlarged view of portion 12 in FIG. 5. The dashed broken line shown in the figures is for the purpose of illustrating portions of the pool skimmer net and forms no part of the claimed design. The dot-dash broken line in the figures indicates cutoff boundaries for the enlarged detailed view and forms no part of the claimed design.
